STOCKING RUN MENDER

Joseph H. Taylor and Hans O. Schomer,
Minneapolis, Minn.

Application November 1, 1946, Serial No. 707,072

9 Claims. (Cl. 66—1.5)

1

This invention relates to stocking run menders and particularly to such as will fill the need for doing the work well, while at the same time be so compact as to be convenient included in a hand bag.

Aside from power machines employed for such work commercially, practically nothing has been done in this field. Other than a needle in a handle with a stop, there appears to be no hand operated device. The needle is of the conventional type with hook and latch for such loop stitch work, like the needle employed in the power machines, and the stop is merely a piece of stiff material clipped onto the shank of the needle. This stop governs the movement of the needle to the right depth into but not upward out of the material. The stocking material is held by a rubber band over the mouth of a tumbler, while being worked on. The length of run that can be worked on in such a setup is quite limited, and it is obvious that it is very difficult to operate the needle free-handedly. It requires a very steady hand and keen eye-sight and under any circumstances is very tedious.

One important object of our invention is to provide a stocking run mender that will make it possible for the average individual to mend a run, and do so rapidly without tiring hands and eyes.

Another object is to provide a stocking run mender that is compact, neat and unobtrusive, so that it may be conveniently contained in a hand bag as well as a sewing kit, to meet emergencies as well as general requirements.

Another object is to provide a stocking run mender that is dependable and efficient in operation, but which can be cheaply manufactured.

Other objects will be apparent from the description and appended claims.

For a full disclosure of our invention, reference is made to the description following and to the drawings, in which—

Fig. 1 is a side elevation view of the stocking run mender.

Fig. 2 is a top plan view.

Fig. 3 is an end view taken from the left as seen in Fig. 1.

Fig. 4 is a sectional view of inner and outer clamping frames taken on any line as indicated by 4—4 in Fig. 2.

Fig. 5 is a separate top plan view of the finder.

Fig. 6 is a view showing details of carriage propelling roller.

In the selected embodiment of our invention, which is hereby disclosed, we provide a construc-

2

tion consisting principally of nickel plated brass and synthetic rubber. It might however be made of aluminum and anodized, destroying any reflective properties and furnishing a contrasting background for material usually worked on. In the main, it consists of a pair of clamping frames for firmly holding the stocking material and a carriage, with the mending devices and aids, operating on and over said clamping frames. We provide outer clamping frame side members 10, preferably of substantially channel shaped sections with outwardly extending flanges, and riveted pins 11 at each end maintain fixed spaced apart relationship of the side members. As to how this outer clamping frame also serves as a track, will be subsequently explained. The inner clamping frame is made up of side pieces 12 and base 13, integrally molded of synthetic rubber, and reinforced by a U-shaped metal member 14, to give stiffness to inner clamping frame in engaging the outer clamping frame. It will be observed that the side pieces 12 are slightly tapered on the outside, to facilitate entry into the outer clamping frame. In the molding of the inner clamping frame, ribs 15 are provided. These ribs have edges that project downwardly, and when pressed downward by the outer clamping frame, exert a barb like grip on stocking material engaged between the two clamping frames. The dark color of the synthetic rubber of the inner clamping frame, provides a helpful contrasting background, against which, the threads of the stocking material are easily seen. To form a similar dark background, aluminum electrolytically or chemically treated, might be employed for inner clamping frame construction.

We provide a frame for carriage for mending devices by using two side members or standards 16, joined together in required spaced apart relationship by riveted connections 17. The top connection is formed by riveting ends of a continuous pin. As will be noted later, this riveted pin also serves as a pivot and as a spring holder. The bottom connections are four short rivets, that join and space the frame with a device to aid in the mending, as will be described later. On each side at the bottom of the carriage frame, a leaf spring 18 is secured to an angle portion of the frame by a rivet 19. This leaf spring has bent loops 20, which resiliently engage under sides of top flanges of the outer clamping frame 10. Another form we have devised, employs within a box-like yoke provided at bottom of each of side standards, a pair of such springs with a junction at the mid-point bent at right angles, so

lateral spring action is also provided. This is an added refinement but not essential to the working of the device. The upper sides of the flanges of clamping frame side members 10 are in slidable contact with a plate 21, which has angle portions 22 at its two ends, which attach it to the carriage frame by further use of the rivets 17. This plate 21 has an opening with opposed index points 23, to define a line at right angles to travel of said plate, the use of which as a finder will be later explained. It will be observed that the top flanges of the outer clamping frame, being thus confined between said plate 21 and said bent spring loops 20, results in smooth sliding of said carriage frame on said outer clamping frame as a track. To propel carriage in a definite and finely controllable manner, and have same remain in a fixed position when not operated, we provide a roller 24 with rubber inserts 25 and a knurled thumb screw 26. This roller has reduced diameter shaft portions 27 journaled into the carriage frame, so that rubber inserts 25 are in frictional contact with top surface of top flanges of outer clamping frame. The knurled thumb screw 26 is force fitted onto shaft portion 27, after the roller has been assembled in the carriage frame. To produce a mender to better accommodate left-handed persons, roller and thumb screw can be reversed. A roller with a thumb screw at each end can be provided, which will then accommodate right handed or left handed persons. In such a roller, a full length replaceable rubber insert can be provided, threaded on a uniform diameter shaft of the size of the journals in the frame. This can also be accomplished with a thumb screw at one end only by using a snap retainer engaging a recess in the other end of the shaft. As will later be explained, needle operating member can be arranged in a manner similar to roller, to better accommodate left-handed persons. It is apparent that by turning the thumb screw, any desired increment of movement forward or backward is obtained. The carriage is readily propelled and slipped off and on the end of the outer clamping frame, but this is not necessary to insert stocking material between the two clamping frames. By placing the inner clamping frame at the proper location inside of a stocking, it may be pressed into the outer clamping frame and the stocking material is firmly secured, ready to be worked on.

To mend a run in a stocking, a conventional hook and latch needle 28 is used, and by forming consecutive loop stitches with succeeding cross threads of the stocking material, the run is eliminated. It is obvious that much refinement is required to do the work quickly and perfectly. Such refinement is made possible by the construction specified aided by certain additional devices. We provide a needle operating member consisting of, a yoke 29 pivotally secured to carriage frame side members 16 by pivots 30, an arm 31, and operating extension 32 integral with said yoke 29. The operating extension 32 is at right angles to the arm 31, and by forming an angle portion integral with the operating extension at one end, we provide a flat finger push contact 33. Like the propelling roller with a thumb screw on either or both sides, finger push contacts can be provided on either or both sides to accommodate left-handed as well as right-handed persons. A coil spring 34 is connected, at one end to the arm 31, and at its other end to the riveted pin 17. This spring actuates the

needle operating member upwardly, when free retains it in that position, and renders operation in that direction automatic as downward operation is performed by hand. Instead of a coil spring, we can use a torsional spring with equally as good results. The operating member of itself could also be a leaf spring. We have also devised a needle operating member with compression coil springs in a straight up and down slide. The operating extension 32 provides up and down travel limit stops, by top and bottom edges of same coming in contact with the side standards of the carriage frame. The width of the extension is proportioned so that the limit of travel in each direction exactly meets the requirements. A horizontal slot 35 is centered in the needle operating member passing through the operating extension. Into this slot, fits a needle holder 36. This needle holder has a projection bend extending forward through the horizontal slot, and the bend itself has a vertical slot in line through both sides. Into this vertical slot, fits a hook and latch needle, which is frictionally and adjustably held against the flat surface of the operating member, by exact spacing of the slot relative to angle bends of needle holder on opposite side of operating member and which provide for its retention. Being thus frictionally held, the needle holder is readily adjustable laterally by moving same in the horizontal slot of operating member. The hook and latch needle 28 is marked to indicate how far it should be inserted into the needle holder for best operation. The needle operating member is so designed, that needle approaches and passes through the work with proper angulation, to insure operation of hook and latch to pick up the stitch. To mend a wide run, additional vertical slots in needle holder would accommodate a plurality of needles, to accomplish the work more rapidly.

To render the mender more subject to fine control of the propelling roller, and to make it more easy to accomplish the mending operation, we provide a magnifying glass 37 at proper focal distance in a pivoted mounting 38. The index points 23 of the finder 21 previously referred to, define a line close to the work, which intersects with the path of the needle, and with the threads of the stocking material in contrast with the dark back-ground of the inner clamping frame, the mending operation is made easy by the further aid of the magnifying glass. The magnifying glass mounting 38 makes further use as a pivot of the riveted pin 17 of the carriage frame, which pin as previously stated also serves to hold the upper end of spring 34. It will be noted that the pin 17 is in an offset portion of the frame side member 16. This makes it possible to swing the magnifying glass through an arc entirely clear of the needle holder, so that same is easily adjusted and the needle may be adjusted or changed without interference. It may be desirable in starting, to swing the magnifying glass aside, and also when tying the final loop, so these operations can be accomplished without interference.

From the foregoing, it will be apparent that the difficult and almost impossible feat of mending by hand a run in a stocking, is reduced to an easily workable process by our invention. It may be accomplished anywhere and under any circumstances, as the mender is so small and compact that it is easily carried. Carefully developed mechanical refinements are substituted for action

of human hand and eye, and so combined that the results are assured, because of automatic controlled operation and in and out movement of needle, fine control of progress of needle, material firmly secured between clamping frames, a magnified view, indexed by points of a finder close to the work, and contrasted by dark background of inner clamping frame.

While we have shown and described a preferred form of our invention, it is obvious that many changes, which are within the scope of our invention will be apparent to those skilled in the art. We therefore desire to be limited only by the scope of the appended claims.

What we claim is:

1. A stocking run mender, comprising an inner clamping frame, an outer clamping frame, a carriage mounted on and movable on said outer clamping frame as a track, said inner clamping frame being constructed of resilient material of dark color, a metal channel reinforcing same, tapered sides having barb like ribs to firmly engage material between it and said outer clamping frame, said carriage consisting of two side members, riveted cross members, and spring friction detents movably holding carriage on track, said carriage having mounted thereon a hook and latch needle, a needle holder, a needle operating member, a propelling roller, a magnifying glass and a finder, said needle holder having said needle vertically adjustably mounted in same, and said holder in turn being horizontally adjustably mounted in a slot in said needle operating member, said operating member being joined to a pivoted yoke and having an operating extension with a finger push contact on one side for actuating same, having up and down travel limit stops, and a one way action and return-to-neutral position coil spring, said propelling roller being journaled into said carriage, and having rubber inserts engaging track surfaces of said outer clamping frame and a rotatable grip at one end propelling carriage by friction to true relative position, said magnifying glass being pivotally mounted on top of said carriage to swing clear of needle holder, said finder encircling said needle and having diametrically opposed index points in line with said needle and with mounting on said carriage to conveniently clear said outer clamping frame.

2. In a stocking run mender, the combination of an inner clamping frame of dark colored resilient material, reinforced with metal, and having tapered sides and lengthwise ribs with downwardly projecting edges on said sides, an outer channel section clamping frame, which is engaged within by said inner clamping frame from below, a carriage comprising two side standards, conveniently located riveted cross members, spring friction detents engaging under sides of top flanges of channel section outer clamping frame, a pivoted needle operating member with up and down travel limit stops and a finger push contact on one side integral therewith, said member having a hook and latch needle and a holder providing for vertical and horizontal adjustment of said needle, a spring to return needle to upward neutral position, a carriage advancing roll, journaled into said carriage, and having rubber insert contacting surfaces against said outer clamping frame and a rotatable enlarged portion at one end of said roll to frictionally propel said carriage, a magnifying glass movably mounted on top of said carriage, and an index point finder, fixedly mounted near bottom of said carriage,

registering with mean operative position of said needle and to gage advance required of said carriage.

3. In a device of the character described in combination, a pair of stocking clamping members complementary to each other and fitting one within the other to engage stocking material therebetween, the inner member made of molded rubber over a metal frame having tapered sides to readily engage the outer member, said sides having molded ribs adapted to grip said stocking material, said outer member consisting of a pair of metal channels with outwardly extending flanges and held in spaced apart relationship by riveted pins, a carriage consisting of a pair of side members held in spaced apart relationship by riveted cross members, spring friction detent means engaging said outer clamping member to cause same to also serve as a track for said carriage and to hold said carriage in a firm though smoothly movable manner on said track, said carriage having mounted thereon a pivoted spring positioned member, a hook and latch needle in adjustable up and down and sidewise position on said member, said member having a convenient operating contact on one side and up and down travel limiting stops, a carriage advancing roll member in frictional contact with said outer clamping member having rubber contact inserts and a rotatable thumb screw at one end, magnifying glass means adapted to travel with and cover the field of operation of the needle while also being adjustable to an off position to change or adjust the needle, and finder means traveling with the needle to denote its operative position and provide a sight for said needle to engage the respective threads of the run in the stocking aided by said magnifying glass.
4. In combination, a slidable carriage comprising side frames and conveniently located cross members between said side frames, a pivoted yoke and an arm extension integral therewith, a mounting on said arm, a hook and latch needle in said mounting, said mounting having a projection bend through a horizontal slot in said arm extension, said bend having a vertical slot engaged by said needle, whereby said needle is frictionally but vertically adjustably held against said extension arm and said needle being similarly horizontally adjustable by shifting said mounting in said horizontal slot, a tension spring between said arm extension and a cross member of said carriage to provide for upward movement of needle, a finger contact on one side transversely of said extension arm, up and down needle travel limiting stops, a magnifying glass, a pivoted mounting on top of said carriage for said magnifying glass adjustable to off-work position, a finder having an index transverse of said carriage fixedly mounted near bottom of said carriage, said index registering with point of entry of needle into work, propelling means for said carriage so that carriage may readily be moved and progressed either way a definite amount from a position which unattended remains fixed, spring friction detents on each side at bottom of carriage so constructed as to engage a track in a firm though smoothly movable manner, track means engaged by said carriage and said friction detents, said track means also serving as an outer clamping frame for holding a stocking between it and an inner clamping frame means, the stocking being gripped by a resilient serrated material of said

inner clamping frame means, which is slightly wedge shaped and engaged by said outer clamping frame means, said resilient material being dark in color, provides a contrasting background for working on light colored threads of the stocking material, all substantially as shown and described.

5. In a device of the character described, in combination, a pair of inter-engaging clamping frames, a mender slidably mounted on the top and external of said pair of clamping frames, said outer clamping frame constructed of a section having both vertical and lateral stiffness to form a track for said mender, and with joined ends to form a clamping frame, an inner clamping frame engaging said external clamping frame to hold securely an area of a stocking therebetween, said inner clamping frame comprising substantially a U shaped section of molded resilient material, outer sides tapered inwardly toward top to facilitate entry into external clamping frame, serrated ribs lengthwise of said outer sides with pointed edges extending downwardly to firmly grip said stocking, a U shaped section metal member molded within said resilient material to stiffen said inner clamping frame, said resilient material being dark in color to provide a back-ground in contrast to light colored stocking material, a mender comprising a hook and latch needle, a needle oscillating member, up and down travel limiting stops for said oscillating member, means for gripping said needle and readily adjusting same to a defined operating position vertically and to a proper position with respect to the work horizontally, spring means to retain said needle in said oscillating member in a neutral out-of-the-work position when not actuated and to furnish proper spring action for operating needle, requiring force of the hand only in one direction with spring reacting in the other direction to return the needle, a magnifying glass in a mounting positioned to cover field of operation of the needle and pivoted for off-work position, a finder with index in registry with operation of said needle at plane of work, side and cross member means to provide a frame to support the several parts of the mender and facilitate its operation by providing for double uses of members as a pivot, a mounting and a spring holder, a leaf spring attached to each side of frame at bottom, a rounded loop at each end of said spring in firm though smoothly movable contact with said outer clamping frame section, and a carriage advancing roll member, journaled into said frame, having resilient frictional contacts engaging said external clamping frame, and a thumb screw at one end of member for definitely advancing said carriage.

6. In a stocking run mender, in combination, a hook and latch needle, a needle holder with needle adjustable vertically and holder itself adjustable laterally, a needle operating member having a mounting for said needle holder, a carriage for said needle operating member, up and down travel limiting stops, a resistance return-to-neutral position spring for said operating member, and clamping frame means to firmly engage section of stocking material worked on and to also provide means for slidably holding said carriage supporting said needle operating member.

7. In a stocking run mender, in combination, an outer clamping frame, an inner clamping

frame, a hook and latch needle and means for operating said needle in mending a stocking held between said clamping frames and means for mounting said needle for travel upon said outer clamping frame, said means arranged so that needle is subject to minute and precise adjustment backward and forward as required and unless definitely actuated retains that adjustment, a magnifying glass and a finder with index points on said mounting means, both in constant registry with point of operation of said needle, said outer clamping frame consisting of side members held in spaced apart relationship by end cross members, said side members having outwardly extending flanges engaged by said mounting means when slidably positioned thereon.

8. In a device of the character described in combination, an outer clamping frame of firm material and slightly rounded inner edges, an inner clamping frame of molded resilient material with draft to facilitate entry into said outer clamping frame, serrated ribs around said inner clamping frame having thin edges extending downwardly to grip material secured between said clamping frames, a stiffening section member molded within said resilient material to maintain shape relative to said outer clamping frame, a hook and latch needle for mending material held between said clamping frames, means for operating said needle at proper angle and between predetermined limits of up and down travel for mending said material, and means for mounting said needle operating means for travel upon said outer clamping frame, said means arranged so that needle is subject to precise adjustment backward and forward as required and said adjustment is retained unless definitely actuated.

40 9. In a stocking run mender, in combination, a hook and latch needle, a laterally adjustable needle holder with needle adjustable vertically therein, a needle operating member engaging said needle holder and provided with up and down travel limiting stops and spring loaded for upward position a carriage for said needle operating member, clamping frame means to firmly engage section of stocking material worked on and to provide for travel on same of carriage for said needle operating member, a roller having a thumb screw at one end removably journaled into said needle operating member carriage, replaceable inserts of resilient material threaded on said roller in frictional contact with each side 45 of said clamping frame means, providing any desired increment of movement forward and backward of said needle operating member carriage by turning said thumb screw.
